UNITED STATES PATENT OFFICE

116,377

DESIGN FOR A CRANE BRIDGE OR SIMILAR ARTICLE

Hiram H. Ostrander, Norris, Tenn.

Application April 26, 1939, Serial No. 84,581

Term of patent 14 years

To all whom it may concern:

Be it known that I, Hiram H. Ostrander, a resident of Norris, in the county of Anderson and the State of Tennessee, have invented a new, original, and ornamental Design for a Crane Bridge or Similar Article, of which the following is the specification, reference being had to the accompanying drawings, forming part thereof, in which

Fig. 1 is a perspective view of a crane bridge or similar article embodying my new design;

Fig. 2 is a top plan view of the article shown in Fig. 1;

Fig. 3 is a front elevational view of the article shown in Fig. 1; and

Fig. 4 is an end elevational view of the article shown in Fig. 1.

The dotted line disclosure of the tracks and housing member shown in Figs. 2, 3 and 4, have been omitted from Fig. 1 for convenience of illustration.

I claim:

The ornamental design for a crane bridge or similar article, substantially as shown and described.

HIRAM H. OSTRANDER.
